UNITED STATES PATENT OFFICE.

EMMERICH FRISCHMUTH, OF BERLIN, GERMANY, ASSIGNOR TO THE SIEMENS & HALSKE ELECTRIC COMPANY OF AMERICA, OF CHICAGO, ILLINOIS.

ELECTRIC-RAILWAY SYSTEM.

SPECIFICATION forming part of Letters Patent No. 657,487, dated September 4, 1900.

Application filed February 12, 1900. Serial No. 4,920. (No model.)

To all whom it may concern:

Be it known that I, EMMERICH FRISCHMUTH, a subject of the German Emperor, residing at Berlin, in the Empire of Germany, 5 have invented a certain new and useful Improvement in Electric - Railway Systems, (Case No. 329,) of which the following is a full, clear, concise, and exact description, reference being had to the accompanying drawings, forming a part of this specification.

My invention relates to electric - railway systems, and has for its object the provision of improved means for the suspension of trolley-conductors employed in such systems.

15 More particularly, my invention relates to improved means for suspending the said trolley - conductors upon curves, turnouts, or other places where the path of the conductor does not lie in a straight line, so that trolley-poles with sliding contact or whose size is otherwise sufficient to make it difficult for the same to pass such curves without coming into contact with the span - wires or other means employed for the support of the said 20 trolley - conductor move safely around the said curves without danger of breaking contact therewith or being otherwise disturbed in their line of travel.

The usual suspensions employed in those 30 railway systems in which the current is collected from the trolley-wire by means of a trolley-wheel placed upon a trolley-pole and conducted from thence to the motors are applicable only to single-track roads in such 35 systems in which broad trolley-poles—as, for instance, such as are adapted to effect sliding contact with the trolley - wire—are utilized. In double-track roads the span-wire which supports the trolley-conductor which is upon 40 the inner side of the curve or which unites the usual “single pull-off” trolley-conductor support of this conductor to the trolley-support holding the outer conductor of the curve is in most instances so low that the sliding-contact trolley-pole or other trolley-pole of similar construction is not able to pass the curves without coming into contact with the span-wire, thereby frequently breaking contact with the trolley-wire and in some instances rupturing the span-wire. Generally speaking, my invention provides a means

whereby the usual suspensions employed in electric - railway systems which utilize the trolley-wheel may be likewise employed in systems in which the current is conducted 55 from the trolley-wire to the motors of the car by means of a sliding-contact trolley-pole.

In its preferred embodiment my invention consists in the provision of an improved trolley-conductor support for the outer wire of 60 curves, this trolley-conductor support being preferably provided with an adjustable vertical extension, through which I preferably pass the span-wire secured to the trolley-conductor support of the inner wire. This span-wire I preferably attach to a suitable anchor-pole, an insulator being preferably provided in the said span-wire to guard against leakage of current. I preferably secure the span-wire attached to my improved trolley-conductor support holding the outer wire of the 65 curve to the same supporting means to which the first aforesaid span-wire is attached, an insulator being also preferably provided in the second span-wire.

70 I will describe my invention more particularly by reference to the accompanying drawings, illustrating the preferred embodiment thereof, in which—

Figure 1 illustrates the application of my 80 improved trolley - conductor support to an electric-railway system, trolley - poles being shown as engaging the trolley-wires. Fig. 2 illustrates the modification of the apparatus shown in Fig. 1.

85 Like parts are indicated by similar letters of reference in both figures.

Two cars *a a*, which are adapted to be operated in a double-track electric-railway system in opposite directions upon the two tracks 90 thereof, are each shown as provided with a trolley-pole *b b*. Trolley-conductors *c d*, in this instance shown as portions of a curve of the electric-railway system, are adapted to convey current to the cars *a a* through the agency of 95 the trolley-poles *b b*, which have a sliding engagement therewith. The trolley-conductor *c* is in this instance the outer conductor of the curve, while the trolley-conductor *d* in this instance is the inner conductor of the same 100 curve. The trolley-conductor support, which may be of any well-known type, may be em-

ployed for supporting the inner trolley-wire *d*. I employ a trolley-conductor support *f* of my improved construction to support the outer trolley-conductor *c*. I preferably provide this trolley-conductor *f* with a vertical extension *g*, which is preferably provided with a vertically-adjustable screw-threaded post *h*. The top of this post *h* is preferably provided with a recess or grooved head *i*. A span-wire *k* serves to unite the trolley-conductor support *f* to a supporting means *l*, preferably provided upon a rigid portion *l'*. I preferably conduct the span-wire *m*, which is secured to the inner trolley-conductor support *e*, through the groove or hole provided in the head *i* of the outer trolley-conductor support *f* and then secure the same to the same supporting means *l* employed for securing the span-wire *k*, which is united to the outer trolley-conductor support. Insulators *n n* are shown as being interposed between portions of the span-wires *k* and *m* to guard against short-circuits or leakage of current to the supporting means.

In Fig. 2 I have shown the two span-wires *k* and *m* as united and then secured to the supporting means *l* by means of an auxiliary wire *o*, an insulator being preferably provided therein. It is seen from the figure that by the use of the improved apparatus of my invention the span-wire *m*, united to the inner trolley-conductor support *e*, is sufficiently elevated above the plane of the trolley-conductors, so that the trolley-poles carried upon the cars may round curves without danger of coming in contact therewith, thereby securing an unbroken engagement between the trolley-pole and the trolley-conductor and obviating the other objectionable features incident to the other systems above referred to. The direction of the forces exerted by the trolley-wire upon the span-wires is indicated by the arrows. By the use of the screw-threaded vertically-adjustable post *h* it will be seen that an easy and ready means of adjustment of the positions of the trolley-conductors may be effected.

While I have herein shown and particularly described the preferred embodiment of my invention, it is obvious that changes may readily be made in the construction and arrangement of the parts herein shown without departing from the spirit thereof, and I therefore do not wish to limit myself to the precise construction herein shown; but,

Having thus described my invention, I claim as new and desire to secure by Letters Patent—

1. In a double-track electric-railway system, the combination with the two conductors for the two tracks, of span-wires extending to said conductors, the span-wire for one conductor crossing the other conductor, and means for elevating said crossing span-wire an extent to prevent its interfering with the current-collecting device, which travels along the conductor which it crosses.

2. In a double-track electric-railway system, the combination with the two conductors for the two tracks, of span-wires extending to said conductors, the span-wire for one conductor crossing the other conductor, supports for the conductors serving as media of attachment of the span-wires to the conductors, and means on the support of the crossed conductor for elevating the span-wire of the other conductor an extent to prevent its interfering with the current-collecting device traveling along such crossed conductor. 75

3. In an electric-railway system, the combination with the trolley-conductors thereof, of a trolley-conductor support supporting one of the said trolley-conductors, a second trolley-conductor support by which the second aforesaid trolley-conductor is supported, and a vertical extension provided upon the second trolley-conductor support whereby the span-wire attached to the first aforesaid trolley-conductor support is passed over the second trolley-conductor support, substantially as described. 80 85 90

4. In an electric-railway system, the combination with the trolley-conductors thereof, of a trolley-conductor support supporting one of the said trolley-conductors, a second trolley-conductor support by which the second aforesaid trolley-conductor is supported, and a vertical extension provided upon the second trolley-conductor support whereby the span-wire attached to the first aforesaid trolley-conductor support is passed over the second trolley-conductor support, the said span-wire and the span-wire attached to the second trolley-conductor support being attached to the same supporting means, substantially as described. 95 100 105

5. In an electric-railway system, the combination with the trolley-conductors thereof, of a trolley-conductor support supporting one of the said trolley-conductors, a second trolley-conductor support by which the second aforesaid trolley-conductor is supported, a vertical extension, and an adjustable post mounted in said vertical extension whereby the span-wire attached to the first aforesaid trolley-conductor support is passed over the second trolley-conductor support, substantially as described. 110 115

6. In an electric-railway system, the combination with the trolley-conductors thereof, of a trolley-conductor support supporting one of the said trolley-conductors, a second trolley-conductor support by which the second aforesaid trolley-conductor is supported, a vertical extension, and an adjustable post mounted in said vertical extension whereby the span-wire attached to the first aforesaid trolley-conductor support is passed over the second trolley-conductor support, the said span-wire and the span-wire attached to the second trolley-conductor support being attached to the same supporting means, substantially as described. 120 125 130

7. In an electric-railway system, the com-

bination with the trolley-conductors thereof, of a trolley-conductor support supporting one of the said trolley-conductors, a second trolley-conductor support by which the second aforesaid trolley-conductor is supported, a vertical extension, an adjustable post provided in the said extension, and a recessed head which is adapted to receive the span-wire attached to the first aforesaid trolley-conductor support, substantially as described.

8. In an electric-railway system, the combination with the trolley-conductors thereof, of a trolley-conductor support supporting one of the said trolley-conductors, a second trolley-conductor support by which the second aforesaid trolley-conductor is supported, a vertical extension, an adjustable post provided in said extension, and a recessed head which is adapted to receive the span-wire attached to the first aforesaid trolley-conductor support, the said span-wire and the span-wire attached to the second trolley-conductor support being attached to the same supporting means, substantially as described.

9. In an electric-railway system, the combination with the trolley-conductors thereof, of a trolley-conductor support, supporting one of the said trolley-conductors, a second trolley-conductor support by which the second aforesaid trolley-conductor is supported, a vertical extension, a post having screw-threaded engagement with the said extension and being vertically adjustable thereof, and a recessed head which is adapted to receive the span-wire attached to the first aforesaid trolley-conductor support, substantially as described.

10. In an electric-railway system, the combination with the trolley-conductors thereof, of a trolley-conductor support supporting one of the said trolley-conductors, a second trolley-conductor support by which the second aforesaid trolley-conductor is supported, a vertical extension, a post having screw-threaded engagement with said extension and being vertically adjustable thereof, and a recessed head which is adapted to receive the span-wire attached to the first aforesaid trolley-conductor support, the said span-wire and the span-wire attached to the second trolley-conductor support being attached to the same supporting means, substantially as described.

11. In an electric-railway system, the combination with the trolley-conductors thereof, of a trolley-conductor support supporting one of the said trolley-conductors, a second trolley-conductor support by which the second aforesaid trolley-conductor is supported, a vertical extension, a post having screw-threaded engagement with the said extension and being vertically adjustable thereof, a re-

cessed head which is adapted to receive the span-wire attached to the first aforesaid trolley-conductor support, and insulators provided in the said span-wire, substantially as described.

65

12. In an electric-railway system, the combination with the trolley-conductors thereof, of a trolley-conductor support supporting one of the said trolley-conductors, a second trolley-conductor support by which the second aforesaid trolley-conductor is supported, a vertical extension, a post having screw-threaded engagement with said extension and being vertically adjustable thereof, a recessed head which is adapted to receive the span-wire attached to the first aforesaid trolley-conductor support, the said span-wire and the span-wire attached to the second trolley-conductor support being attached to the same supporting means, and insulators provided in the said span-wires, substantially as described.

70

13. In an electric-trolley-conductor support, the combination with a post portion thereof, of a vertical extension *g* provided thereon, a vertically-adjustable post *h* in engagement with the said vertical extension, and a head *i* provided on said adjustable post, substantially as described.

75

14. In an electric-railway system, the combination with curved portions of trolley-conductors thereof, of a trolley-conductor support supporting one of the said trolley-conductors, a second trolley-conductor support by which the second aforesaid trolley-conductor is supported, and means whereby the span-wire attached to the first aforesaid trolley-conductor support is passed over the second trolley-conductor support, substantially as described.

80

15. In an electric-railway system, the combination with curved portions of trolley-conductors thereof, of a trolley-conductor support supporting one of the said trolley-conductors, a second trolley-conductor support by which the second aforesaid trolley-conductor is supported, and means whereby the span-wire attached to the first aforesaid trolley-conductor support is passed over the second trolley-conductor support, the said span-wire and the span-wire attached to the second trolley-conductor support being attached to the same supporting means, substantially as described.

85

In witness whereof I hereunto subscribe my name this 18th day of January, A. D. 1900.

EMMERICH FRISCHMUTH.
